SECTIONAL PILE SHELL

Albert C. Titcomb, Boston, and Mark D. Cronan, Belmont, Mass., assignors to New England Foundation Company, Inc., Boston, Mass., a corporation of Massachusetts

Application November 18, 1943, Serial No. 510,712

14 Claims. (Cl. 61—78)

This invention relates to improvements in superposed sectional pile shells adapted to be driven into the ground to receive a suitable filling such as concrete.

Such pile shells are usually made of superimposed, thin sheet metal sections and it is practically impossible to drive such shells of substantial length into the ground by blows applied to the upper end of the uppermost section. Means have therefore been employed heretofore for driving the several sections independently and simultaneously by securing to each pile section a driving ring of greater external diameter than that of the section to which it is secured and simultaneously driving all the sections by a driving core having suitably spaced shouldered members adapted to engage the upper faces of the respective drive rings, thereby distributing the force of the blow of the pile hammer simultaneously to the several sections.

In some cases the drive rings have been secured to the upper ends of the respective sections, while in others the drive rings have been so connected to the lower ends of the respective sections as to pull the sections downwardly by tensile force.

It has been found in actual practice that it is difficult, if not impossible, so to construct and assemble the shell sections and the drive rings which are connected to them that the distances between the drive rings of the several sections will be precisely the same as the distance between the shoulders of the driving core and any difference in the distances between two drive rings and that between the corresponding shoulders of the driving core will cause a separation or rupture of the shell sections which will permit seepage of water and/or of fine soil into the interior of the pile shell which will adversely affect the homogeneity of the filling or will cause such weakening or deformation of a shell section that it will collapse upon withdrawal of the driving core.

One means of avoiding such defects in sectional shell constructions is disclosed in our prior Patent No. 2,288,576 granted June 30, 1942, in which each pile section has a drive ring secured to its upper end provided with a coupling member and complementary coupling means rigid with the lower end of the shell section forming a bayonet joint, but so constructed as to permit limited relative longitudinal movement of the members of the bayonet joint between adjacent shell sections.

In such constructions packing means are usually provided between the lower end of each

shell section and the driving ring on the upper end of the next lower section to prevent seepage through the joint. While such constructions are mainly effective the amount of slippage of the joint connection is necessarily limited.

The present invention comprises an improvement upon our prior construction, the principal object of which is to provide means for permitting greater extent of longitudinal movement between adjacent shell sections and for providing more effective means for preventing seepage through the joints connecting the several sections.

A further object of the invention is to provide a sectional pile shell construction in which the means connecting adjacent superimposed sections are such as to permit not only the use of thin metal shell sections but also shell sections, sleeve couplings and drive rings of any suitable material, such as plastics, impregnated paper, plywood, or other materials which may be stamped, formed, rolled, moulded, or shaped and united as hereinafter shown and described.

More particularly the object of the invention is to provide a pile shell section having at its upper end a drive ring and having slidably and rotatably mounted on its lower end a coupling ring to provide a slip joint therebetween with complementary coupling means on said drive ring and said coupling ring and which can be permanently assembled at a factory and so that the shell section can be readily connected in the field with another similarly equipped shell section.

A further object of the invention is to provide a slip joint having such frictional engagement between the coupling ring and the lower portion of the shell upon which it is mounted as normally to support the weight of shell sections assembled above or below it, but adapted to be rotated by an applied turning force to cause interlocking engagement of the coupling means of the coupling ring and that of the drive ring of another shell section.

Broadly the object of the invention is to provide a sectional pile shell construction in which one or more of the several shell sections are extensible.

These and other objects and features of the invention will more fully appear from the following description and the accompanying drawings and will be particularly pointed out in the claims.

Illustrative and preferred embodiments of the invention are shown in the accompanying drawings as applied to a pile shell having a plurality

of superimposed cylindrical sections of progressively increasing diameter from the lowermost to the uppermost, but it will be understood that the invention may be embodied in sectional pile shells of any desired shape or contour, of constant diameter, uniformly tapering sections, shells having horizontal or spiral corrugations, etc.

In the drawings:

Fig. 1 is a vertical longitudinal sectional view of a pile shell embodying the preferred form of the invention and illustrating in elevation a driving core simultaneously engaging the drive rings of the several sections and the drive shoe connected to the lower end of the lowermost section, the lower end of the adjacent sections being connected to the driving ring of the next lower section and/or to the drive shoe by a coupling ring having a sliding connection therewith and suitable packing for preventing seepage through the joint therebetween;

Fig. 2 is a horizontal sectional view on line 2—2 Fig. 1, illustrating one form of bayonet joint connection between the drive shoe and the coupling ring and a slip joint connection between the coupling ring and the lower end of a shell section of the lowermost shell section and also illustrative of similar bayonet and slip joint connections between the drive rings of the successive sections and the lower end of the next superimposed section;

Fig. 3 is a detail side elevation of the construction illustrated in Fig. 2;

Fig. 4 is a fragmentary vertical sectional view of a modified bayonet joint and slip joint connection between the drive ring on the upper end of one section and the lower end of the next superimposed section, illustrating also a portion of the drive core having a shoulder engaging the drive ring;

Fig. 5 is a similar fragmentary view illustrating another form of bayonet joint and slip joint connection;

Fig. 6 is a similar fragmentary view of a modified form of bayonet joint and slip joint connection;

Fig. 7 is a similar fragmentary view of a modified form of bayonet joint and slip joint connection of the character illustrated in Fig. 1;

Fig. 8 is a similar fragmentary view of another form of bayonet joint and slip joint connection showing a modified form of packing between the coupling ring and the lower end portion of the next superimposed section in which the coupling ring surrounds and has a bayonet joint connection with the vertical wall of the drive ring and also illustrates a drive ring having a horizontal lower ground-engaging face instead of an upwardly inclined lower face;

Fig. 9 is a similar fragmentary view illustrating another embodiment of the invention in which the coupling ring is connected to the drive ring in a manner similar to that illustrated in Fig. 8; and,

Fig. 10 is a similar fragmentary view illustrating a screw threaded connection between the coupling ring and the drive ring.

The invention comprises broadly a tubular pile formed of superimposed shell sections adapted to be driven into the ground to receive a suitable filling in which each shell section and also the drive rings, coupling rings, and drive shoes are of material capable of withstanding the pressure of the soil in which it is embedded and having a drive ring fixedly connected to its upper end and

extending over and beyond its circumference provided with a lower soil-penetrating face and an upper face to be engaged by a shouldered member of a driving core and having an upwardly extending wall provided with a member of an interlocking joint connection, said shell section having rotatably and slidably mounted upon its lower end portion a coupling ring provided with an interlocking joint connection complementary to that of the drive ring adapted to be rotated into interlocking engagement with a like coupling member upon the drive ring of the next lower shell section, and thereby providing a slip joint connection between adjacent pile sections which will avoid the application to the respective shell sections of tensile or compressive strains which will tend to rupture or distort the walls of the respective shell sections.

The shell sections may be of any suitable material, such as sheet steel, plastic, impregnated wood, ply wood, etc., capable of being stamped, formed, rolled, moulded, or otherwise shaped to any desired contour and may be provided with horizontal, spiral or vertical corrugations.

The shell sections may be of uniform diameter uniformly tapered or otherwise formed in accordance with the character of the soil or of the use to which the pile is to be subjected.

The lower end of the pile shell may be provided with a conical driving point or preferably with a flat drive shoe connected to the lower end of the lowest pile section by a slip joint connection as herein described.

A preferred embodiment of the invention which is illustrated in Figs. 1, 2, and 3, of the drawings, comprises a series of superimposed thin shell sections 1 each of which has fixedly secured to its upper end a drive ring 2 and which desirably has fixedly secured to its lower end a sleeve 3 upon which is rotatably and slidably mounted a coupling ring 4, the drive ring and coupling ring being provided with complementary interlocking joint connecting members adapted when the coupling ring at the lower end of one section is interengaged with the complementary locking member of the drive ring of the next lowest section to form a tight joint therebetween, suitable gaskets preferably being interposed between the members of the sliding connection between the coupling ring and the sleeve, and preferably also between the coupling ring and the drive ring to prevent seepage of water, etc., into the interior pile shell.

As illustrated in Figs. 1-3 each drive ring 2 is provided with a downwardly extending flange 5 which fits tightly within the shell section 1 and is fixedly secured thereto in the manner above described. The drive ring is provided at or adjacent its periphery with an upwardly extending wall 6 provided with suitably spaced members of an interlocking joint connection which, as illustrated more particularly in Figs. 2 and 3, comprises inwardly extending vertical wall sections or ribs 7 united by inwardly extending wall sections or ribs 8, the lower faces 9 of which are suitably inclined to the horizontal.

The sleeve 3 which is secured to the lower end of each shell section 1 has an inward offset 10 and cylindrical portion 11 of smaller diameter provided at its lower end with a U-shaped flange 12 having a vertical wall 13 spaced from and parallel to the outer surface of the sleeve 11. The coupling ring 4 has a portion 14 which slidably fits upon the vertical section 13 of the U-shaped flange and is provided at its upper end with a reversely bent U-shaped section 15 which is com-

plementary to that of the shell section and slidably fits the cylindrical wall of the sleeve 11. A suitable packing or gasket 16 desirably is interposed between the parallel portions of the flanges of the sleeve and the coupling ring thereby providing a watertight joint. The lower end of the portion 14 of the coupling ring 4 is provided with suitably spaced outwardly extending ribs 17 complementary to the inwardly extending ribs 8 of the drive ring and having inclined upper surfaces 18 adapted to engage the inclined surfaces 9 of the ribs 8, the lower end of the coupling ring being also provided with a downwardly extending annular portion 19 adapted to engage a gasket 19 which is seated upon a shoulder on the drive ring adjacent to the vertical wall 6 thereof.

By reason of the construction above described the outwardly offset ribs 17 of the coupling ring may be introduced vertically into the spaces 20 between the inwardly extending walls 7 of the drive ring and rotation of the coupling ring will cause the inclined faces of the ribs 17 thereof to engage the complementary inclined faces of the ribs 8 of the drive ring and force the lower end of the coupling ring tightly against the gasket 19, thereby clamping it firmly upon the shoulder of the drive ring, thus sealing the joint connection against seepage of water into the interior of the pile.

In the construction illustrated in Fig. 1 the shell sections are shown as cylindrical shells of successively decreasing diameter, but it will be understood that the shell sections may be of uniform diameter, horizontally or spirally corrugated, or of uniformly tapered construction.

The lower end of the lowermost shell is similarly connected to the drive shoe 21 the periphery of which is provided with an upwardly extending wall 22 provided with an interlocking joint connection similar to that of the respective drive rings.

Suitable means are provided for driving the shell sections independently which as illustrated herein comprises a driving core 23 having suitably spaced shoulders 24 adapted simultaneously to engage the driving surfaces of the respective drive rings. The lower end of the drive core is provided with a horizontal surface 25 adapted to engage the complementary flat upper surface of the drive shoe 21.

By reason of the construction above described the drive shoe and each of the drive rings of the several sections are simultaneously driven by blows of the hammer impinging upon the upper end of the drive core and any slight variation in length of the shell sections is compensated by the slip joint connections respectively between the drive shoe 21 and the lowermost shell to which it is secured and by the slip joint connections between the adjacent shell sections, while the gaskets 19 prevent seepage through the interlocking joint connection and the gaskets 16 prevent seepage through the relatively movable surfaces of the slip joint connection.

Desirably the slip joint connection between the respective coupling rings and sleeves is such as to provide sufficient friction to support the weight of other shell sections which may be superimposed upon or depending from the shell sections.

The construction above described is such that each unit may be completely manufactured and assembled at the factory and adapted when in the field to be coupled to other sections and a suitable drive shoe to form a complete pile shell adapted to be driven into the ground.

A modified preferred form of coupling is illustrated in Fig. 4 in which each shell section 1 has fitting within and secured to its lower end portion a sleeve 26 having an inwardly offset cylindrical portion 27 the lower end of which is provided with a horizontal laterally extending flange 28. A coupling ring 29 slidably and rotatably fits upon the inwardly offset section and is provided with a recess containing a gasket or packing 30. The lower end portion of the coupling ring has an outwardly offset cylindrical extension 31 the lower end portion of which is provided with suitably spaced offset coupling members or ribs 32 complementary to the inwardly offset ribs 8 of the vertical walls 6 of the drive ring 2 which is fixedly secured to the upper end of the next lowermost shell section 1. In this construction, as in that disclosed in Figs. 1-3, the coupling ring 29 is firmly locked to the drive ring of the next lower section and the gasket 19, which is interposed between the lower end of the coupling and the drive ring, is firmly clamped in place. The coupling ring 29 is prevented from detachment from the sleeve 26 by the horizontally extending flange 28 upon the lower end of the sleeve and the movement of the coupling ring upon the sleeve is limited by the flange and the upper wall of the inwardly offset portion.

A modified and simplified construction embodying the invention is illustrated in Fig. 5 in which the shell section 1 has fitting within and secured to its lower end portion a sleeve 33 which has secured to its lower end a circumferential band 34 forming in effect an outwardly extending flange. The coupling ring 35 is of generally cylindrical form and slidably fits upon the band 34 and has secured to its upper end portion a similar band 36 which forms in effect an inwardly extending flange which fits upon the periphery of the sleeve 33. The lower end of the coupling ring is provided at suitable intervals with outwardly offset sections 37 similar to those illustrated and described in Fig. 1 which engage the inwardly offset ribs 8 of the vertical wall 6 of the drive ring 2 of the next lowermost section.

A suitable gasket or packing 38 is interposed between the adjacent walls of the shell and coupling ring 35 and may be held in place by suitable means such as a ring 39 fixedly secured to the coupling ring. In this construction as in that shown in Figs. 1-3 the lower end of the coupling ring is adapted to engage the gasket 19 and firmly clamp it upon its seat on the drive ring.

Another embodiment of the invention is illustrated in Fig. 6 in which the lower end of the shell 1 has secured to it an annular inner band 40. In this construction the coupling ring is of deformed U-shape having a cylindrical portion 41 which is rotatably and slidably mounted upon the lower end portion of the shell section 1 and provided with a recess containing a packing or gasket 42. The coupling ring is provided with suitably spaced outwardly offset shouldered portions or ribs 43 adapted to engage complementary shoulders extending inwardly from the upper end of the wall 6 of the drive ring 2. The walls 44 of the shouldered portions 43 extend downwardly and are provided with inwardly offset portions 45 which are integral with the annular inclined seat 46 of the coupling which engages the inclined upper face of the drive ring. The coupling ring has an inner vertical wall 47 extending upwardly within the shell 1 in sliding engagement with the band 40 of the shell and is provided at its upper end with an outer band 48.

which tightly fits the inner surface of the shell 1. Another embodiment of the invention is illustrated in Fig. 7 in which the lower end of the shell section 1 has secured to its outer surface a sleeve 49 the lower end of which has an inwardly extending U-shaped flange 50 the upper end of which is provided with an outwardly extending periphery 51. The coupling in this construction is of general deformed U-shaped construction and has a cylindrical portion 52 which slidably fits upon the sleeve 49 and is provided with outwardly offset spaced sections 53 adapted to interlock with similarly spaced inwardly projecting ribs 54 on the upper end of the wall 6 of the drive ring 2. The coupling 52 has an inwardly and downwardly extending portion 55 complementary to the inclined upper surface of the drive ring and is provided with an inner vertical wall 56 the upper end of which has an inverted U-shaped flange 57 which slidably fits between the inner surface of the sleeve 49 and the periphery 51 of the complementary U-shaped flange of the sleeve 49. A suitable packing 58 is housed in the space between the interengaging U-shaped flanges of the sleeve and the coupling ring and a suitable gasket 59 is enclosed between the complementary inclined surfaces of the coupling ring and drive ring, thereby insuring exclusion of seepage into the interior of the pile.

Another embodiment of the invention is illustrated in Fig. 8. In this construction the lower portion of the shell section 1 has fixedly secured to it a cylindrical sleeve 60 provided with a plurality of inwardly offset ribs 61 which may be of annular or spiral form and provided with suitable recesses to receive packing rings 62 or a spiral packing. The lower end of the sleeve 60 is provided with a horizontal outwardly extending flange 63.

The coupling ring comprises a cylindrical section 64 which is rotatably and slidably mounted upon the sleeve 60 and provided with an offset cylindrical portion 65 which fits the periphery of the flange 63. The lower end of the coupling ring is provided with spaced inwardly offset sections 66 complementary to similar outwardly offset sections 67 of a vertical wall 68 of the drive ring 69 of another shell section, thereby forming a bayonet joint connection of the character heretofore described. In this construction the wall 68 is spaced from the periphery of the drive ring and the drive ring provided with a concentric outer peripheral wall 70, portions of which are adapted to engage the outer face of the coupling ring when the bayonet joint connection is in interlocked engagement. The lower portion of the coupling ring 65 is adapted to seat upon a suitable shoulder 71 between the adjacent walls 68 and 70 of the drive ring.

In the construction illustrated in Fig. 8 the drive ring at the upper end of each section is shown as extending horizontally outwardly from the shell section to the upper end of which it is fixedly secured and it will be understood that drive rings for the several pile sections may be so constructed as to have horizontal outwardly extending ground-engaging surfaces or inclined ground-engaging surfaces in this construction or in any of the other constructions illustrated herein, the form of the drive ring in any case being optional so long as positively interengaging joint members are provided for the drive ring and coupling ring and the coupling ring is slidably and rotatably mounted upon the lower end of the next superimposed shell section.

Another modified construction embodying the invention is illustrated in Fig. 9 in which the shell section 1 has fitting within and fixedly secured to it a downwardly extending cylindrical sleeve 72, the lower end of which is provided with an outwardly extending flange 73. The coupling ring comprises a cylindrical section 74 which rotatably and slidably fits upon the sleeve 72 and is provided with an annular recess containing a gasket or packing 75. The coupling ring has an outwardly offset cylindrical section 76 the lower end portion of which is provided with suitably inwardly extending walls or ribs 77 having inclined upper faces adapted to engage complementary offset sections 78 of a bayonet joint coupling member upon the upper end of a vertical wall 79 extending upwardly from the periphery thereof. The drive ring 2 is provided with an outer or peripheral wall 80 of less height providing therebetween a seat for a gasket 81 and the lower edge of the coupling ring is so constructed as firmly to clamp the gasket upon its seat on the drive ring when the bayonet joint members are moved into locking position.

Another embodiment of the invention is illustrated in Fig. 10 in which the lower end of the shell section 1 is provided with an outer cylindrical band 82 forming in effect a flange at the lower end of the shell section. A coupling ring 83 of general cylindrical form is rotatably and slidably mounted upon the cylindrical band 82 and has secured to the inner face of its upper end a similar cylindrical band 84 which slidably and rotatably engages the outer cylindrical surface of the shell section 1. The coupling ring 83 is provided intermediate of its width with a spirally offset section or rib 85 and at its lower end with a cylindrically offset section 86 the lower end of which is adapted to engage a suitable gasket 87 and clamp the same firmly against a shoulder upon the drive ring.

In this construction the drive ring 2 has an outer vertical peripheral wall 88 which is provided with an inwardly offset spiral section or rib 89 complementary to the outwardly offset section or rib 85 of the coupling ring. The upper end of the peripheral wall 88 of the drive ring has an inwardly extending flange 90 the under surface of which is spirally inclined to engage the upper surface of the outwardly offset member or rib and together with the inclined surface 91 of the spiral section or rib 89 provides interengaging screw thread connection between the coupling and the upwardly extending wall of the drive ring. A suitable packing 92 is interposed between the cylindrical portion of the coupling ring and the shell section 1 and is held in place in any suitable manner as by a ring 93 which is secured to the coupling ring.

In the manufacture of the shell sections each of the drive rings is formed by usual shaping machines to provide the downwardly extending flange which engages the upper end of a shell section and with the upwardly extending wall or walls and the interlocking coupling members thereon.

The embodiments of the invention illustrated in the figures of the drawings include gaskets or suitable packing interposed between the coupling ring and the sleeve which is attached to the lower end of each shell section for the purpose of providing a watertight joint where the pile is to be sunk in water-saturated soil and similar gaskets are also shown in some of the figures

of the drawings as interposed between the lower end of the coupling ring and the shoulder of the drive ring upon which it seats. It will however be understood that under certain conditions such as where the pile is driven in dry soil the packings and the recesses containing them can be omitted thereby simplifying the construction and minimizing the cost of manufacture.

In each of the constructions shown in Figs. 1-3, 4, 5, 8, 9, and 10, the coupling ring can be separately formed and shaped in suitable machines and slidably moved upon the sleeve section sufficiently to enable the outwardly extending flange to be formed upon, or if in the form of a band, to be applied to the lower end of the shell section; while in the construction shown in Figs. 6 and 7 the coupling ring will be assembled upon the lower end of the shell section or sleeve and the flange upon the upper end thereof thereafter united to or formed upon said vertical wall within the shell (Fig. 6), or within the sleeve 49 (Fig. 7), before the sleeve is secured to the lower end of the shell section.

It will be understood that the embodiments of the invention shown and described herein are of an illustrative character and not restrictive and that various changes in form, construction and arrangement of parts may be made within the spirit and scope of the following claims.

Having thus described the invention, what is claimed as new, and desired to be secured by Letters Patent, is:

1. A pile shell, adapted to be driven into the ground to receive a suitable filling, comprising a plurality of axially superimposed tubular shell sections each of which has fixedly secured to its upper end a driving ring having coupling means and presenting a shoulder adapted to be driven individually and simultaneously with others by one of the shoulder members of a driving core, and a coupling member having coupling means complementary to and engaging that of the drive ring of the next lower section, slidably mounted upon the lower end of each section by a slip joint permitting limited longitudinal movement of said section.

2. A pile shell, adapted to be driven into the ground to receive a suitable filling, comprising a plurality of axially superimposed tubular shell sections each section having fixedly secured to its upper end a rigid drive ring having at or adjacent its periphery an upwardly extending wall provided with a member of an interlocking joint connection, and a coupling ring having a complementary member of said interlocking joint connection rotatably and slidably mounted on the lower end portion of said pile section engaging the joint connection member of the drive ring of the next lower section, and means for limiting the longitudinal movement of the coupling ring along the section upon which it is mounted.

3. A pile shell, adapted to be driven into the ground to receive a suitable filling, comprising a plurality of axially superimposed tubular shell sections each section having fixedly secured to its upper end a rigid drive ring having at or adjacent its periphery an upwardly extending wall provided with a member of an interlocking joint connection, and a coupling ring having a complementary member of said interlocking joint connection rotatably and slidably mounted on the lower end portion of said pile section, with a packing therebetween, and engaging the joint-connecting member of the drive

ring of the next lower section, means for limiting the longitudinal movement of the coupling ring along the section upon which it is mounted, and a gasket between the coupling ring and the drive ring, said interlocking means having means operable by rotative movement of the coupling ring into coupling position to engage and clamp the gasket tightly upon the drive ring.

4. A pile shell, adapted to be driven into the ground to receive a suitable filling, comprising a plurality of axially superimposed tubular shell sections each section having fixedly secured to its upper end a rigid drive ring having at or adjacent its periphery a circular upwardly extending wall provided with a member of an interlocking joint connection having a rib inclined to the horizontal, a coupling ring rotatably and slidably mounted on the lower end of said pile section having an interlocking joint member provided with a cooperating inclined rib adapted upon rotative engagement with the interlocking joint member of the drive ring on the upper end of the next lower pile section, and means for limiting the longitudinal movement of the coupling ring.

5. A pile shell, adapted to be driven into the ground to receive a suitable filling, comprising a plurality of axially superimposed tubular shell sections each section having fixedly secured to its upper end a rigid drive ring having at or adjacent its periphery a circular upwardly extending wall provided with a member of an interlocking joint connection having a rib inclined to the horizontal, a coupling ring rotatably and slidably mounted on the lower end of said pile section having an interlocking joint member provided with a cooperating inclined rib adapted upon rotative engagement with the interlocking joint member of the drive ring on the upper end of the next lower pile section, means for limiting the longitudinal movement of the coupling ring, and packing means respectively between the coupling ring and shell and between the coupling ring and drive ring of the next lower shell section for preventing ingress of liquid into the interior of the pile.

6. A pile shell, adapted to be driven into the ground to receive a suitable filling, comprising a plurality of axially superimposed sections each section having secured to its upper end a drive ring having at or adjacent its periphery an upwardly extending circular wall provided with a member or members of a bayonet joint connection, a cylindrical sleeve fitting, and secured to the lower end portion of said shell section provided with a U-shaped flange, a coupling ring having a complementary inverted U-shaped portion rotatably and slidably engaging and fitting the sleeve and flange thereof to provide a slip joint, a packing filling the space between the overlapping walls of said coupling ring and flange, and complementary bayonet joint members on said coupling ring and flange adapted when the bayonet joint members of the coupling ring and those of the next lower section of the driving ring are interlocked to secure said sections firmly together subject to relative longitudinal movement between the coupling ring and the pile section upon which it is mounted.

7. A pile shell, adapted to be driven into the ground to receive a suitable filling, comprising a plurality of axially superimposed sections each section having secured to its upper end a drive ring having at or adjacent its periphery an upwardly extending circular wall provided with a

member or members of a bayonet joint connection, a cylindrical sleeve fitting within and fixedly secured to the lower end of said shell provided below said end with a cylindrical inwardly offset portion the lower end of which has an outwardly extending inverted U-shaped flange, a coupling ring having a complementary inverted U-shaped portion rotatably and slidably engaging and fitting the surface of the inwardly offset portion of said sleeve, and the flange thereof, to provide a slip joint therebetween, a packing filling the space between the overlapping walls of said coupling ring and flange, and complementary bayonet joint members on said coupling ring and flange adapted when the bayonet joint members of the coupling ring and those of the next lower section of the driving ring are interlocked to secure said sections firmly together subject to relative longitudinal movement between the coupling ring and the pile section upon which it is mounted.

8. A pile shell, adapted to be driven into the ground to receive a suitable filling, comprising a plurality of axially superimposed tubular shell sections each of which has mounted upon its upper end a drive ring having coupling means, a coupling ring slidably and rotatably mounted on its lower end portion having coupling means complementary to that of said drive ring, and packing means between said coupling ring and the portion of the shell section upon which it is mounted, the frictional engagement of the coupling ring and sleeve being sufficient to support the weight of the shell sections assembled thereon but to permit rotation by an applied turning force to move the coupling means thereof into locking engagement with the complementary coupling means on a like drive ring from another shell section.

9. As an article of manufacture a tubular pile shell section having fixedly secured to its upper end a rigid drive ring extending over and beyond the circumference thereof and provided with a member of an interlocking joint connection, a coupling ring slidably and rotatably mounted on the lower end portion of said section provided with a member of an interlocking joint connection complementary to that of said drive ring adapted upon rotative movement of said coupling ring fixedly to engage a like locking member of the drive ring of another pile section, and means for limiting the sliding movement of the coupling ring.

10. As an article of manufacture a tubular pile shell section having fixedly secured to its upper end a rigid drive ring extending over and beyond the circumference thereof having a gasket-supporting shoulder and provided with an inclined member of an interlocking joint connection, a coupling ring slidably and rotatably mounted on the lower end portion of said section provided with an inclined member of an interlocking joint connection complementary to that of said drive ring adapted upon rotative movement of said coupling ring fixedly to engage a like locking member of the drive ring of another pile section and to clamp said gasket firmly upon the shoulder thereof, and means for limiting the sliding movement of the coupling ring.

11. As an article of manufacture a tubular pile

shell section having fixedly secured to its upper end a rigid drive ring extending over and beyond the circumference thereof and having an outer upwardly extending wall provided with an inclined coupling member and having a seat for a gasket adjacent to the base of said wall, a sleeve fixedly secured to the lower end portion of said shell section having at its lower end a laterally extending flange, a coupling ring slidably and rotatably fitting said sleeve above said flange and having an inclined coupling member complementary to that of said drive ring adapted upon interlocking engagement with that of a like drive ring to clamp the gasket firmly upon its seat and the drive ring thereon.

12. As an article of manufacture a tubular pile shell section having fixedly secured to its upper end a rigid drive ring extending over and beyond the circumference thereof and having at or adjacent its periphery an upwardly extending wall provided with members of a bayonet joint connection, a sleeve fixedly secured to the lower end of said shell section having a cylindrical inwardly offset portion provided at its lower end with an outwardly extending flange, a coupling ring slidably and rotatably mounted upon and tightly fitting said inwardly offset portion having at its lower end members of a bayonet joint connection complementary to those of the drive ring, and a packing between the coupling ring and the offset portion of the sleeve upon which it is mounted.

13. As an article of manufacture a tubular pile shell section having fixedly secured to its upper end a rigid drive ring extending over and beyond the circumference thereof and having a peripheral upwardly extending wall provided with inwardly offset inclined coupling members and having a seat for a gasket within and adjacent to the base of said wall, a sleeve fitting and fixedly secured to the lower end of said shell section having at its lower end a laterally and upwardly extending U-shaped flange, a coupling ring having a complementary inverted U-shaped flange rotatably and slidably engaging said sleeve and the flange thereof to provide a slip joint therebetween and having outwardly offset inclined coupling members complementary to those of said drive ring.

14. As an article of manufacture a tubular pile shell section having fixedly secured to its upper end a rigid drive ring extending over and beyond the circumference thereof and having a low outer upwardly extending circumferential wall and an inner upwardly extending wall of greater height provided with outwardly offset inclined coupling members of an inclined bayonet joint and having between said walls a gasket-receiving channel, a sleeve fitting and fixedly secured to the lower end of said shell section having at its lower end an outwardly extending flange, a coupling ring mounted on said sleeve with a packing therebetween and having an outwardly offset portion fitting the offset portion of the inner wall of said drive ring and provided with inwardly extending bayonet joint members complementary to those of said wall and having at its lower end an extension adapted to engage the gasket in the channel of said ring.
